DESIGN FOR A FENCE PANEL

Nelson J. Hays, Burbank, Calif.

Application February 26, 1948, Serial No. 144,747

Term of patent 3½ years

(Cl. D28—1)

To all whom it may concern:

Be it known that I, Nelson J. Hays, a citizen of the United States, residing at Burbank, county of Los Angeles, State of California, have invented a new, original, and ornamental Design for Fence Panel, of which the following is a specification, reference being had to the accompanying drawing, forming a part thereof, and in which drawing:

Fig. 1 is a front perspective view of a fence panel, showing my new design,

Fig. 2 is a front elevation of one of the sections of the fence panel,

Fig. 3 is a rear elevation of the section shown in Fig. 2, and

Fig. 4 is a top plan view thereof in a folded position.

I claim:

The ornamental design for a fence panel, substantially as shown.

NELSON J. HAYS.
